UNITED STATES PATENT OFFICE

2,488,727

ELECTRODE FOR ELECTRIC DISCHARGE
DEVICES

Hendrik Anne Klasens, Mitcham Junction, and
Thomas Holmes, London, England, assignors
to General Electric Company, a corporation of
New York

Application January 7, 1948, Serial No. 854
In Great Britain January 13, 1947

1 Claim. (Cl. 176—122)

1

This invention relates to electric discharge devices and in particular to discharge lamps of the cold starting type filled with gas and/or metal vapor at a low pressure. When a sufficiently high voltage is applied between the electrodes of such a tube the lamp strikes. The cathode losses are high initially but decrease when the electrodes are heated up by the discharge until a final equilibrium is reached whereby the voltage drop near the cathode is small but just enough to keep it at the requisite emitting temperature.

It is a disadvantage of the conventional types of electrodes, consisting of a metal wire coated with emitting material, that the coating disintegrates during life, especially during the period when the electrodes are heating up and the cathode losses are high. The life of the lamps is shortened by this disintegration. Moreover the sputtered material will be deposited on the glass wall near the electrodes causing an unsightly blackening. It is known that the life of the tube can be improved by using a solid rod of emitting material enclosed in a wire helix. The emitting surface still disintegrates but the emission is continuously restored by diffusion of the emitting material, for example an alkaline earth metal, from the inside to the surface. This does not prevent however the deposition of sputtered material on the glass.

It is an object of our invention to provide an electrode of the cold starting type which will have a very long life. Other objects are to provide an electrode which is highly resistant to disintegration, heats up quickly upon starting of the discharge and requires only a small voltage drop to keep it at the requisite temperature during operation, and minimizes or practically eliminates blackening of the surrounding envelope.

Other objects and advantages of our invention will appear from the following description and from the drawing which is a somewhat diagrammatic elevation of one end of a gaseous discharge lamp embodying an electrode comprising our invention.

According to the present invention, in an electric discharge lamp of the type referred to above and comprising a sealed envelope 1 filled with gas and/or metal vapor at low pressure, the electrodes 2 are constituted of hollow bodies made of an alloy of one or more alkali metals or alkaline earth metals with a metal or metal alloy capable of forming a substantially homogeneous alloy therewith. Preferably the alkaline earth metal used is barium and it is alloyed with nickel

5 or a nickel-copper alloy. The surface of such emissive alloys can be made strongly emitting by mild oxidation (e. g., by heating in an atmosphere of oxygen) whereby a thin layer of metal oxide is formed, followed by heating in a vacuum at such temperature that the alkali metal or alkaline earth diffuses to the surface. In this way a surface layer is formed, comprising inter alia the free alkali metal(s) or the free alkaline earth metal(s) or a mixture of these metals, together with the oxide(s) of the said metal(s).

10 The said alloy may be made by melting together nickel and barium in the absence of air, e. g., in the atmosphere of argon. To prevent evaporation of barium, chromium may be added, and a certain percentage of copper may also be added to increase the solubility of the barium.

A suitable composition is:

	Per cent
20 Barium	0.5
Chromium	1.0
Copper	10.0
Nickel, balance.	

25 The material is drawn into tube form, and the tubes are activated by heating for about 20 seconds in oxygen at 10^{-2} mm. pressure, for instance, by means of induction coils.

Conveniently, the electrode 2 according to 30 the invention is in the form of a tube closed at one end, and according to a further feature of the invention the internal diameter of the electrode is so related to the pressure and nature of the gas filling that during the operation of the 35 lamp the discharge covers only the inside of the tube, i. e., the so-called "hollow cathode effect" is obtained. In the case of a discharge lamp filled with argon at about 3 mm. pressure, an internal diameter of 2 mm. is satisfactory.

40 It will be understood that each end of the envelope 1 is provided with an electrode 2 which may be supported by a lead-in conductor 3.

According to a further feature of the invention 45 a shield 4 which may be in the form of a plate may be positioned adjacent the open end of the electrode 2 so as to cover the opening while leaving sufficient space for the discharge to pass between the shield and the inside of the electrode. In this way any blackening of the envelope 50 of the lamp near the electrode, which in any case is greatly diminished because the sputtering takes place only inside the electrode and nearly all the sputtered material is collected on the electrode itself, is substantially eliminated as sputtered material escaping from the open

end of the electrode will be collected on the shield. A slight bombardment of the outside of the electrode may still take place and cause sputtering of metal and blackening of the envelope, but this may be prevented by coating the outside of the electrode with an insulator, such as glass as indicated by the dotted outline 5.

Electrodes made according to the invention have a very long life, not only because the emitting layer strongly adheres to the metal carrier but also because any loss in emitted material is replenished from the body of the electrode. Another advantage is that heat losses by convection are low, so that the electrodes are heated up very quickly on starting and only a small voltage drop is necessary to keep them at the requisite temperature during operation of the lamp.

What we claim as new and desire to secure by Letters Patent of the United States is:

In a gaseous electric discharge device, an elec-

trode comprising a hollow body composed of a substantially homogeneous alloy containing mainly nickel together with approximately 10% copper, 1% chromium and 0.5% barium.

HENDRIK ANNE KLASENS.
THOMAS HOLMES.
